UNITED STATES PATENT OFFICE.

WILLIAM G. RECTOR, OF WINDSOR, MISSOURI, ASSIGNOR OF ONE-HALF TO STEWART B. STURGIS, OF LEETON, MISSOURI.

HAMMOCK-SUPPORT AND CANOPY THEREFOR.

1,097,941.

Specification of Letters Patent.

Patented May 26, 1914.

Application filed February 4, 1914. Serial No. 816,544.

To all whom it may concern:

Be it known that I, WILLIAM GRANT RECTOR, a citizen of the United States, residing at Windsor, in the county of Henry and

5 State of Missouri, have invented certain new and useful Improvements in Hammock-Supports and Canopies Therefor; and I do hereby declare the following to be a full, clear, and exact description of the invention, such as will enable others skilled in the art to which it appertains to make and use the same.

10 The primary object of this invention is to provide a simple and practical hammock support which may be moved from place to place and which, when not in use, may be folded into a very compact form.

15 Another and more specific object of the invention is to provide a hammock support, including a base piece, having transverse foot pieces hinged to the ends thereof, carrying standards, and means for holding said standards in an upright position.

20 As a further object, the invention contemplates the provision of a canopy adjustably connected to the standards, so as to be properly disposed over the hammock.

25 With these and other objects in view as will become more apparent as the description proceeds, the invention consists in certain novel features of construction, combination and arrangement of parts as will be hereinafter more fully described and claimed.

30 For a complete understanding of my invention, reference is to be had to the following description and accompanying drawings, in which—

35 Figure 1 is a side elevation of my hammock support, the canopy being partly broken away, Fig. 2 is an end elevation of the support, Fig. 3 is a section taken on the plane of line 3—3 of Fig. 1, Fig. 4 is a detail view, showing the means provided 40 for locking the standard supports to the base piece, Fig. 5 is a transverse section taken on the plane of line 5—5 of Fig. 1, Fig. 6 is a horizontal section taken on the plane of line 6—6 of Fig. 1, Fig. 7 is a 45 fragmentary side elevation, showing a slightly modified form of my invention, wherein a brace bar connected to the upper ends of the standards is employed, and Fig. 50 Fig. 8 is a section taken on the plane of line 8—8 55 of Fig. 7.

Referring in detail to the drawings by numerals, 1 designates the base of the hammock support, which is in the form of a plank, and to the ends of which are secured, by means of hinges 2, transverse foot pieces 3. The hinges are secured to the upper faces of the base and foot pieces so that the latter may swing over the former.

5 Each foot piece has secured to its outer edge a pair of standards 4 and 5, the inner edges of which are straight and disposed in spaced parallel relation. The standards may be of any desired shape and material, and are connected by a strap 6. Between each pair of standards is disposed a hammock hook 7, which is connected to a cross-piece 8, supported between suitable fasteners 9. It will be noted upon reference to Fig. 1 that the crosspieces 8 engage the outer faces of the standards 4 and 5 and that the shank of the hook swings between said standards, so that considerable weight is removed from the fasteners 9.

10 To support each pair of standards in a vertical position, I provide a brace or strut 10, which is pivoted at its upper end between the standards by means of a rod 11 which passes transversely through said standards and strut. The lower end of the strut rests upon the base 1, and is removably locked thereto by fastening means 15 which I will now describe.

15 The fastening means comprises a longitudinal bar 12, which is rigidly secured to the base 1, and which is formed with a slot 13 opening upon its inner end in which is received a headpiece 14 secured to the lower end of the strut 10. A latch bar 15 is pivoted at one end to the top of the bar 12 adjacent its outer end and is formed with 20 an edge opening notch 16 which receives the strut 10 and prevents the lower end thereof sliding inwardly. An angular flange or stop plate 17 is formed on one edge of the bar 12 and the bar 15 swings under this plate 25 and is therefore held against upward movement. It will be apparent that when the plate 14 is within the slot 13, and the latch bar 15 in position, the strut 10 will be securely fixed with respect to the base 1.

30 If desired, a brace bar 18 may be used supplementary to or in place of the strut 10. This bar is formed upon its terminals with longitudinally projecting tongues 19 which project between each pair of standards and 35

which are supported upon bolts 20. When the bar is in position, the shoulders 21 engage the inner faces of the standards 4 and 5, so that said standards will not be drawn together by the weight of the hammock and its occupant.

The canopy, which I use in connection with the hammock support, comprises a frame having end sections, each composed 10 of a standard 22 and rods 23 which diverge upwardly and outwardly. The lower terminals of these rods and standards are connected pivotally to bands or collars 24 which surround the upper ends of the support 15 standards 4 and 5, whereas the upper ends of the rods and standards 22 are connected to longitudinal frame bars 25. A covering 26 is connected to and supported by the canopy frame, as clearly illustrated in the 20 drawings. To support the rods 23 in proper relation with respect to the standards 22, I provide the braces 27, the outer ends of which are hooked into engagement with said rods, and the inner ends of which are 25 connected to sliding collars 28 mounted on the standards 22 and locked in any desired position by means of set screws 29.

To provide for an adjustment of the bands or collars 24 so that the canopy may be 30 raised and lowered, I secure to the outer edge of each of the standards 4 and 5 adjacent their upper ends, rack bars 30 having upwardly facing teeth for engagement by locking pins 31. These pins extend 35 through the outer bars of the bands 24, as best shown in Fig. 6, have their outer ends connected by a bridge-piece 32 and are normally held in engagement with the rack bars 30 by means of contractile helical 40 springs 33 connected to the bridge-piece 32 and to the bands 24. When it is desired to adjust the height of the collars 24, the locking pins 31 are drawn from engagement with the toothed rack 30 by means of handles 34, after which the collars may be 45 moved to the desired position. The canopy may be detached from the standards 4 and 5 by being slipped over the upper terminals thereof and when not in use may be folded 50 to a very compact form by swinging the rods 23 against the standards 22.

From the foregoing description taken in connection with the accompanying drawings, it will be apparent that I have provided 55 a very simple and practical hammock support which may be quickly set up for use and which may, when not in use, be folded into a very small form, convenient for storage. Although the support has been

described for use primarily in connection 60 with a hammock, other devices, such as swings, may be connected thereto.

While I have shown and described the preferred embodiment of my invention, it will be understood that minor changes in construction, combination and arrangement of parts may be made without departing from the spirit and scope of the invention as 65 claimed.

Having thus described my invention, I 70 claim:—

1. In a support of the character described, a basepiece, a standard hingedly connected to said basepiece to fold thereagainst, a strut pivoted at one end to said standard 75 and extending toward the basepiece at an acute angle, and means for locking said standard against movement relative to the base, comprising a bar secured longitudinally of the base having an inwardly opening slot at one end thereof to receive the strut, a locking bar pivoted to said first mentioned bar, having an edge opening slot to receive the strut, and means carried by said first mentioned bar to overhang the 80 latch bar.

2. In a device of the character described, a basepiece, a standard hingedly secured at one end to said basepiece to fold thereagainst, a strut pivotally connected at one 90 end to the standard and extending into engagement with the basepiece, said strut having a head formed on its free end, and locking means for the strut comprising a bar secured longitudinally of the basepiece and 95 formed with a slot in its inner end to receive said head, a latch bar pivoted at one end and formed with an edge opening notch to receive the strut, and a stop secured to said first mentioned bar and projecting over 100 the latch bar to hold the latter against upward movement.

3. In a hammock support, a basepiece, a pair of standards projecting upwardly at one end thereof and having their opposed edges in spaced relation, a transverse bar crossing the space between said standards, means connecting said bar to the outer faces of the standards, and a hook connected to said bar to swing through the space between 110 said standards.

In testimony whereof I affix my signature in presence of two witnesses.

WILLIAM G. RECTOR.
